HUMIDIFYING SYSTEM

Otto J. Kuenhold, Shaker Heights, Ohio, assignor to Monmouth Products Company, Cleveland, Ohio, a corporation of Ohio

Application July 31, 1935, Serial No. 34,047

2 Claims. (Cl. 261—104)

My invention pertains to a system for adding moisture to the air in rooms and similar spaces and controlling the percentage of humidity maintained therein, said system being adaptable for 5 operation in conjunction with either warm air, hot water or steam heating plants.

The particular advantages of my humidifying system are: the utmost attainable simplicity of structure, installation and operation; continuous, trouble-free operation; adaptability of the 10 main operating principles to all types of heating systems; accuracy and convenience of control; constant visible evidence that the system is operating showing how much moisture is being added 15 to the air; automatic downward graduation of the per cent of humidity maintained as weather gets colder and upward graduation as weather gets warmer so that window condensation will not materially increase as weather gets colder, yet 20 the room humidity will be held at highest practicable per cent, regardless of out-door temperature changes. Other advantages will be apparent during the course of the following description.

25 To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

35 In said annexed drawings:

Fig. 1 is a diagrammatic presentation of my humidifying system including its variations to adapt it to radiator heating systems, or warm air heating systems employing either an evaporating pan as represented in Fig. 1a, or a water spray as represented in Fig. 1b, in the casing of the furnace.

Fig. 2 shows a plan view of the evaporating pan. Fig. 3 shows a vertical longitudinal section 45 through the evaporating pan and a portion of the furnace in which the pan is placed, and taken on line 3—3 of Fig. 2. Fig. 4 shows a vertical transverse section of the evaporating pan on line 4—4 of Fig. 2. Fig. 5 shows a vertical transverse section on line 5—5 of Fig. 2. And Fig. 6 is a chart illustrating the principle of operation of my humidifying system.

Referring to Fig. 1. The water supply for the humidifying system is taken from any convenient 55 domestic water supply pipe 75, at city pressure,

by means of tube 85, and is passed successively through a shut-off valve 80, water filter 50 and pressure governor 100. These parts comprise the water supply means and are fully described in my copending patent application Serial No. 5 21,576, filed May 15, 1935.

The purpose of the water filter is to remove even microscopic floating particles from the water so that there will be no possibility of clogging at any point and to make the employment 10 of such tiny valves as are employed in the governor and wall control instrument practical. The pressure governor reduces the water pressure supplied to the system down to minimum requirement for each type of humidifying system, enables accurate automatic humidity control to be attained and serves other important purposes to be described later.

The perfectly clear water at substantially uniform predetermined pressure is supplied by the 20 pressure governor 100 to supply tube 1 which is extended from the basement upward within a partition wall to the humidity control instrument 200 which is located at convenient height and in an accessible well-lighted location of a central 25 room of the house. After flowing through this control instrument, the water flows through tube 2 down into the basement. From this point tube 2 may be continued as either tube 3, 4 or 5 dependent upon the type of humidifying system 30 that is served by the elements above described.

If tube 2 is continued as tube 3 it supplies water to an evaporating pan 301, illustrated in detail by Figs. 2, 3, 4 and 5.

If a water spray is preferred for introducing 35 moisture to the circulating air, tube 2 is continued as tube 4 which supplies water to a spray 275 through the automatic intermittent valve 251.

If the heating of the rooms is done by steam 40 or hot water radiators, tube 2 is continued as tube 5 which supplies water through the automatic pressure equalizer 351 to main tube 7 from which any number of branches 8 supply water to evaporators 400, mounted in back of each important first floor radiator 298. A branch tube 6 from tube 5 is a main supply tube for the evaporators 401 of all important second floor radiators 299 through branch tubes 9.

The pressure equalizer 351 placed in the main 50 supply tube leading to first floor radiator evaporators 400 is a mercury device which imposes a resistance to the flow of water to first floor radiator evaporators equal to the average differ- 55

ence in hydraulic head between second floor evaporators 401 and first floor evaporators 400.

Should any radiator evaporator be supplied with more water than can be evaporated, by reason of that radiator being shut off or for other reasons, the surplus of water will be drained off by drain tubes 10 and 11 leading to a main drain tube 12 the outlet 13 of which drips into a cellar drain. All vertical tubes are preferably placed within partition walls preferably close to the pipes conducting water or steam to and from the radiators. This prevents freezing of the water tubes leading to or from the radiator evaporators.

In order to comprehend the principles upon which the automatic graduation of the maintained per cent of humidity of my humidifying system is based, certain characteristics of indoor humidified air must be borne in mind. These characteristics, illustrated by the chart Fig. 6 are as follows:

The per cent of air humidity which prevails in a home when no moisture is added and which is hereinafter referred to as the "natural indoor humidity" is shown by curve A which assumes 70 degrees indoor temperature.

The per cent of indoor humidity at which window vapor begins to appear, hereinafter called the "condensation point" is shown by curve B which also assumes 70 degrees indoor temperature. The more the indoor humidity is raised above curve B during any given outdoor temperature, the greater is the condensation occurring upon the windows.

The vertical distance from the natural humidity curve A to the window condensation point curve B, at any given outdoor temperature, indicates the relative amount of moisture which must be added to the indoor air to bring its humidity up to the window condensation point. The volume of water represented by this vertical distance for any given home depends upon the volume of air that leaks into and out of that home.

If sufficient water is evaporated into the air, of a given home, to raise the humidity from the natural humidity, shown by curve A, up to 40 per cent in 35 degree weather, the theoretical per cent of indoor humidity resulting in other weather below about 45 degrees is shown by the dotted line, curve D. It will be noted that the theoretical humidity maintained by this same rate of water evaporation into the indoor air will rise above the window condensation curve B. However, the occurrence of window condensation extracts some moisture from the indoor air and this reduces the actual humidity that is maintained down to curve E.

My system for automatically graduating the indoor humidity is to simply feed water through the wall control instrument 200, Fig. 1 at an accurately maintained rate to the humidifying means, such as the evaporating pan 300, Fig. 1. If the owner adjusts the said control instrument to feed water for evaporation at a rate which results in just reaching the window condensation point in 30 degree weather, then the scale of humidities that will be automatically maintained during colder outdoor temperatures will correspond closely to those indicated by curve D. This scale of maintained humidities will slightly increase window condensation in the colder weather but this modifies the extreme indoor air dryness which would occur if the humidity was held below the window condensation point during extremely cold weather. The results ob-

tained by my system of humidity control are therefore ideal.

The foregoing assumes average wind velocities. Abnormally high or low wind velocity by respectively increasing or decreasing air leakage through the home, will respectively decrease or increase the maintained indoor humidity, but abnormal wind conditions are seldom of more than a few hours' duration. The home occupant can correct any wind influence by simply resetting the rate of water feed.

It is essential in my system of humidity control that the evaporating means have adequate evaporative capacity during 30 to 35 degree weather, when the temperature of the furnace or radiators, which determine the rate of evaporation, are of substantially half their maximum temperature.

When the outdoor temperature rises above about 45 degrees the humidity that would be maintained, shown by curve D, rises to a higher point than is necessary or desirable. To avoid this, I provide means to adjust the evaporative capacity of the evaporators downwardly to the required extent. In the case of the humidifying pan 301, the number of evaporating plates, is reduced and in the case of the radiator evaporators 400 and 401 means are provided for reducing the evaporative capacity as will be subsequently explained.

By limiting the maximum evaporative capacity of the evaporating means as above described, the said evaporators will be unable to evaporate all the water supplied by the water feed instrument 200 Fig. 1 in the warmer winter weather and in consequence the per cent of humidity maintained will conform approximately to curve E in the warmer winter weather.

The present almost universally employed method of controlling the maintained indoor humidity is to use a humidostat. These instruments will maintain the per cent of humidity static at whatever per cent the instrument is set. Line C of the chart shows the ensuing results if the humidostat is set to main 45 per cent humidity. It will be noted that as weather gets colder the maintained humidity will be considerably above the window condensation point shown by curve B. The window condensation occurring increases very rapidly as weather gets colder. The humidostat furthermore causes all water taken from the air by window condensation to be replaced by added evaporation. As a result the window condensation is multiplied to an astonishing extent. The only remedy is to constantly reset the humidostat to comply with weather changes. This serious fault illustrates the great improvement in the state of the art accomplished by my system of control.

The control of the entire system is accomplished from one central point—the control instrument—mounted upon a wall of a central living room at a conveniently accessible location. The turning of a knob is all that is necessary to obtain the maintenance of a per cent of room humidity that will result in no more window condensation than the owner desires. The percentage of humidity automatically adjusts itself according to changes in outdoor temperature. Referring to Fig. 1, the control knob 210 is graduated to show the rate of water feed in, for instance, gallons per day. At 230, the owner can see the water supply dripping through a sealed glass tube. At 240 an indicator shows the existing per cent of room humidity.

Referring to Figs. 2, 3, 4 and 5, the operating characteristics of the humidifying pan will be described:

The pan which is preferably of cast vitreous enameled metal is indicated at 301. The upper face of both sides is notched at 302 and the bottom middle of the pan contains a series of spaced apart, upwardly projecting lugs 303 forming notches 304 which are aligned with notches 302 on each side. The above described spaced notches are adapted to receive and hold in vertical parallel disposition the porous evaporating plates 305.

At the right hand or outer end of the pan, open topped chambers 306 and 308 are formed by walls 310, 309 and 307, Fig. 2. Chamber 306 is an inlet chamber to which water is supplied from the control instrument 200 through tube 3. Chamber 308 is an outlet chamber drained by tube 15. Wall 310 is slightly lower than partition wall 307, but wall 309 is higher than either wall 307 or 310.

When the water entering the inlet chamber 306 has risen to the level of wall 310, it overflows into the pan which is set level within the casing of the furnace, as shown in Fig. 3, preferably resting on top of the furnace castings 16 and 17. The outer casing of the furnace is represented by 18, the usually conical bonnet of the casing is indicated at 19 and the usual inverted cone shaped center of the bonnet is shown at 20. The pan is slid in place through a hole cut in the bonnet so that its center line will preferably pass through the vertical center line of the furnace—assuming a cylindrically shaped furnace. The front flange 320 of the pan remains outside of the casing. The hole in the bonnet to receive the pan is made large enough to admit the pan with the evaporating plates 305 set in place as shown and is closed by a removable plate 21. The flange 320 is tapped to receive the tubes 3 and 15.

The pan acts in part as a water reservoir to present water surface to the heated and hence dried air circulating through the furnace casing into ducts, not shown, leading to the rooms. The principal functions of the pan are, however, to support the evaporating plates 305 and to conduct water to the porous evaporating plates. The evaporating plates 305, being of porous material, absorb the water quite rapidly and are therefore continuously in a wet condition. Their wet vertical surfaces, being continuously "wiped" by the heated and hence excessively dry air, rapidly give up water vapor to the circulating air. Capillary action causes the plates 305 to draw water up from the pan 301 as rapidly as it is evaporated from their surfaces.

The above method of exposing vertical wet surfaces to the generally upwardly moving air increases the evaporative capacity of the pan so that it equals the evaporation which could be obtained from a pan having much greater width, yet the pan can be made so narrow that it offers no appreciable retardance to the air flow.

Another important advantage is that the evaporating plates may be placed centrally as shown in Fig. 3, with reference to the inverted conical top of the furnace which then acts as a spreader to uniformly distribute the water vapor to all air ducts leading from the furnace. If it is then desired to favor ducts leading from the front or back of the furnace, the evaporating plates 305 may be moved more toward the front or back accordingly. The pan 301 may also be swung over toward whichever side of the furnace is to be

favored, or a combination of both expedients may be employed.

Referring now to Fig. 5, it will be noted that the evaporating plates extend sidewise as at 315 beyond the sides of the pan. The sidewise extension is so proportioned with reference to the height of the plates that all portions will remain substantially of equal wetness. Lime and similar salts contained in the water tend to gravitate toward the bottom and outer ends of the wings 315 forming excrescences, which may easily be brushed off when the pan is withdrawn from the furnace.

The middle bottom portion of the evaporating plates which projects into the pan is cut in a substantially vertical direction as at 311 to fit the inside of the pan, but from the highest water level 313 downwardly, the plate is cut at an angle as at 312 to form a bottom point as shown. The bottom point enters the recesses 304, Fig. 3. This holds the plates in vertical position.

When the water level descends to, for instance, level 314, Fig. 5, only a small cross-sectional area of the porous plate is immersed in the water. The volume of water which the plates can lift, and hence the wetness of the plates, is dependent partly upon the cross-sectional area that is immersed in the water and partly upon the average height that the water is lifted. By having the bottom or immersed end of the plate pointed, the amount of water lifted by capillary action and hence the wetness of the plates and the rate at which water is evaporated, is rapidly decreased at lowered water level and rapidly increased by raised water level.

The above characteristic combined with the fact that the pan normally holds only about a quart of water, results in rapid response to increased or decreased rate of water feed to the pan. In general usage, the water level will be at or near minimum in severe winter weather when the furnace is at its hottest and will be at or near maximum in cold weather when the furnace is operated at low capacity.

Should the rate of water feed to the evaporating pan be greater than the pan and plates can evaporate, as for instance in mild weather, then the water level will rise higher than the top of the wall 310 of the inlet chamber as shown at 316, Fig. 4. As soon as the top level of wall 307 is reached, the incoming fresh cold water will overflow into the outlet chamber 308 instead of flowing into the pan. From the outlet chamber, the water is drained by tube 15, which may be led to a cellar drain.

The above method of handling surplus water has several important advantages. Surplus water does not enter the pan to chill it and reduce evaporation, but flows from the inlet chamber 306 into the outlet chamber 308. The overflow water, being fresh, cold water, will not deposit lime in the outlet tube 15 as would be the case if the hot, lime saturated water from the pan overflowed into the outlet tube. Furthermore, the waste of heat due to permitting hot water from the pan to overflow, is eliminated.

My method of supplying an accurately measured volume of water to the evaporating pan greatly reduces chances of overflow. It eliminates float valves or other valves at the pan and so simplifies the structure that no chances for clogging or failure exist. Experience shows that any valve mechanism at the water pan, exposed to heat, moisture and lime deposits cannot be relied upon to remain in operating condition.

An important advantage of the multiple evaporating plate arrangement is the fact that the evaporating capacity can be increased or decreased by merely increasing or decreasing the 5 number of plates. In this way, the evaporative capacity can be made just right so that in milder weather, when less evaporation is required, the pan and plates will evaporate less than the amount of water delivered to the pan by the control instrument.

19 Other modes of applying the principle of my invention may be employed instead of the one explained, change being made as regards the structure herein disclosed, provided the means stated by any of the following claims or the 15 equivalent of such stated means be employed.

I therefore particularly point out and distinctly claim as my invention:

20 1. In a humidifying system for a heated space, the combination of control means for delivering water at a constant rate of flow, means for evaporating water into the air circulated through the space to be heated, a conduit for transmitting water from said control means to said evaporat-

ing means, said evaporating means comprising a water receptacle chamber and a plurality of porous plates projecting transversely and upwardly from said chamber, and means in said chamber for diverting the flow of excess water supplied thereto from passing to that portion of said chamber occupied by said plates.

2. In a humidifying system, means for evaporating water comprising a reservoir, and a plurality of plates composed of water absorbing, 10 porous material, standing on edge and projecting upwardly from said reservoir, the lower portion of said plates being of V-shaped contour, an inlet chamber in said reservoir adapted to overflow into said reservoir, an outlet chamber adjacent said inlet chamber, a dividing wall separating said chambers from each other, and a second dividing wall separating said chambers from said reservoir, said first-named dividing wall being higher than the overflow level of said 15 inlet chamber, and said second dividing wall being higher than said first-named wall.

OTTO J. KUENHOLD.
